(57) **CLAIM**

The ornamental design for a capsule, as shown and described.

DESCRIPTION

FIG. 1 illustrates a top perspective view of an embodiment of a capsule according to the present invention;

FIG. 2 illustrates a front side elevational view thereof, wherein the rear side elevational view is a mirror image of this view;

FIG. 3 illustrates a right side elevational view thereof, wherein the left side elevational view is a mirror image of this view;

FIG. 4 illustrates a top plan view thereof;

FIG. 5 illustrates a top perspective view of a second embodiment of a capsule according to the present invention;

FIG. 6 illustrates a front side elevational view thereof, wherein the rear side elevational view is a mirror image of this view;

FIG. 7 illustrates a right side elevational view thereof, wherein the left side elevational view is a mirror image of this view; and,

FIG. 8 illustrates a top plan view thereof.

1 Claim, 6 Drawing Sheets
